CONTENT DISPENSING DEVICE FOR
COLLAPSIBLE TUBES

Douglas D. Derrick, Olivette, Mo.

Application November 28, 1947, Serial No. 788,625

2 Claims. (Cl. 222—102)

1

This invention relates to improvements in means for holding a collapsible tube and dispensing the contents thereof, and has particular reference to a holding and dispensing device characterized by improved construction and operation, which is especially suitable for use with collapsible tubes containing toothpaste, shaving cream and the like.

An object of the invention is to provide a device of the character indicated, which is capable of accommodating collapsible tubes of various lengths and sizes, and which is adapted for effecting content-dispensing collapse of the tube in a positive and highly effective manner.

Another object is to provide in a device of this nature, tube-collapsing mechanism embodying a positive drive operable to effect an intermittent or step-by-step advance of the collapsing mechanism along the tube, such as to afford at each operation, discharge of a suitable or predetermined desired quantity of the material content of the tube.

A further object is to provide a device of this character, wherein the positive drive of the tube-collapsing mechanism, is readily releasable to permit relatively free displacement of the mechanism, as for return thereof to a starting position.

Yet another object is to provide in a device of the nature indicated, a tube-collapsing mechanism having press rolls arranged for embracing the tube to be collapsed, wherein at least one of the press rolls is releasable for displacement away from the other press roll, such as to facilitate passage of the sealed end of a collapsible tube between the rolls in mounting the tube in the device.

A still further object of the invention is to provide a device of the character above referred to, having a member providing a valve-controlled discharge port and an element on the member for locating the discharge end of the collapsible tube in alignment with the port, wherein the member is readily removable from the device to afford complete access thereto, as for cleaning the valve and port and the tube locating element.

Other objects and advantages of the present invention will appear readily from the following description of a presently preferred embodiment thereof, as exemplified in the accompanying drawing, wherein:

Fig. 1 is a top view of the dispenser device;

Fig. 2 is a front elevational view of the device;

Fig. 3 is an enlarged front sectional view as taken along line 3—3 in Fig. 1, showing the operating mechanism of the device;

Fig. 4 is a section transversely through the device, as taken along line 4—4 in Fig. 3;

Fig. 5 is an enlarged elevation at the lower or discharge end of the device;

Fig. 6 is a longitudinal section through the device at one side of the frame therein;

Fig. 7 is a longitudinal section through the frame and mechanism thereon, and

Fig. 8 is a detail elevation of a part of the tube press mechanism.

With reference now to the several views of the drawing, the present device comprises a frame 10 of suitable rigid material, as sheet metal, formed to provide a bottom wall or base 11 and opposite side walls 12. Base 11 is longitudinally channelled at 14 and 15, and through the bottoms of the channels are two or more openings 16 to cooperate with suitable wall bracket elements or the like (not shown) by which the device is mounted preferably in a vertical position on a wall or other support (not shown). A pair of casing members 18 and 19 each suitably hinged at 20 to the adjacent frame side wall 12, cooperate with the frame bottom wall or base 11 to encase the frame and mechanism, to top extensions 22 of the casing members closing the top end of the frame, while the lower end 23 of the frame is exposed to receive a valved port member later to be described. Spring latch elements 24 are carried by the frame side walls 12 for co-operation with the casing members to retain them in closed position (Figs. 1, 4 and 5), the latch elements readily yielding to manual pressure exerted on the casing members in the opening direction. When the casing members are swung to open positions (broken line showing in Fig. 1), the frame and mechanism are fully exposed.

Centrally of the base 11 near the upper end of the frame, is a clamp or mounting device 25 for the sealed end of a collapsible tube. The clamp hereby preference, comprises a bracket 26 having its base 27 in overlying engagement with the frame base 11 and secured thereto by a screw 45 and wing-nut assembly 28, the screw passing through a slot 30 directed longitudinally in the base 11 whereby to permit positional adjustment of the clamp toward and from the upper end of the frame. Since the collapsible tube when inserted in the device in a manner to appear, has its discharge end associated with a receiver and locating element (to be described) disposed in fixed position relative to the frame, the present longitudinal adjustability of the clamp 25 facilitates the accommodation of collapsible tubes of

various lengths. The clamp bracket 25 upstanding from the frame base 11, carries one jaw 31 of the clamp, and is formed to provide eye portions 32 to receive a hinge bar 34 serving to hinge the movable jaw member 35 to the bracket. Jaw member 35 is extended rearwardly from its jaw portion, to afford an operating handle 36. Between the bracket and handle 36 is a suitable biasing spring 38 acting yieldably to urge the movable jaw 35 toward the fixed jaw 31.

The end of each side wall 12 at the lower or bottom end of the frame, supports or has formed integrally therewith, an inwardly directed flange 39, these flanges forming a mounting seat for a plate member 40 (Figs. 3 and 5). Plate member 40 here is removably supported on the flanges by heated studs 42 fixed to the latter and cooperating with lock-slots 43 in the plate (Fig. 5) to retain the plate in assembly to the frame. A finger piece 44 is provided on the plate 40 to facilitate angular displacement of the plate relative to the studs 42, as for assembly of the plate to the frame seats 39 or to position the plate for removal.

An aperture or discharge port 46 is provided centrally through plate 40, and controlling the port is a valve element 47 of plate form, pivoted to the plate at 48 adjacent the plate margin 50. By preference, the pivotal connection is of a character to retain the valve element in frictional surface engagement with the face of the plate member 40, such that the valve element will remain stationary relative to plate 40, but will yield in manual operation thereof through the handle 51, to a position closing the port 46, or to a position of discharge wherein a port 52 in the valve element registers with port 46. The latter position is determined by abutment of a projection 54 on the valve element, with the plate margin 50, while displacement of the valve element in the port-closing direction may be limited as by a suitable stop 55 on the plate 40 (Fig. 5).

Suitably fixed upon the inner side of plate 40 is a ring member 56 formed of resilient material such as rubber or the like, the ring member presenting a central tapered bore 58 having its small end in marginal registry with port 46. Ring member 56 is provided for receiving and holding the discharge end or outlet neck 59 of a collapsible tube 60 shown in dotted lines in Fig. 7, whereby the tube end is located and retained in alignment with discharge port 46. As will be appreciated, tapering of the bore 58 in locating member 56, adapts the member for the reception of the tube necks of different external diameters, while forming the member of resilient material affords thereby, a substantially fluid-tight seal of the tube neck in the bore 58.

It is to be noted here that in mounting a collapsible tube in the device, the primary mounting support of the tube is effected by the jaw clamp 25 engaging the sealed end 62 of the tube (Fig. 7), with the clamp adjusted longitudinally of the frame 10 according to the length of the tube to be collapsed, such that the tube in effect, is suspended therefrom. As so mounted the tube has its discharge neck 59 bearing in the bore 58 of the locating member 56, with a minimum of pressure sufficient to effect the desired fluid seal between the member and the external side surfaces of the tube neck. Moreover, the described tube mounting is such that the head surface 63 of the tube (Fig. 7) is slightly spaced from or bears only lightly on the margin 64 of the member 56, this being highly desirable in order to

prevent tube rupture at the head end as total collapse of the tube is approached.

Turning now to the presently improved compressor mechanism for effecting tube collapse, each side wall 12 of the frame 10 is provided with a slot 66 substantially coextensive with the longitudinal extent of the side wall, the slots constituting a guide or trackway for the compressor. The compressor assembly is comprised of a carriage member 67 of generally U-shape, affording sides 68 joined by a cross-piece or wall 70. Each side carries a stud 71 having a roller thereon in rolling engagement in the guide slot 66 of the adjacent frame wall 12, the stud including a head 14 at its free end, overlapping the slot margins on the outer side of the side wall (Fig. 3). Each side 68 of the carriage further supports a stud 75 having its outer end seating in the slot 66 of the adjacent frame side wall 12. The studs 75 and 20 rollers 72 suitably relatively spaced on each side of the carriage, thus cooperate with the frame side wall slots 66 to support the carriage between the side walls, for movement longitudinally of the frame.

25 On the carriage are tube press elements or press rolls 76 and 78, arranged between the carriage sides 68 for embracing the tube to be collapsed. Roll 76 is mounted on a shaft or spindle 79 having its ends seated in apertures provided therefor in the carriage sides, and projecting slightly outwardly from the latter, as at 80, for a purpose to appear. The other roll 78 is on a shaft 82 which has its ends extending through slots 84 in the carriage sides 68. Internally of the carriage 30 and adjacent each side 68 thereof, is a position control member 86 for the roll 78. Each of these members is pivoted at its end 87 (Fig. 8) upon the shaft 79 or roll 76, and provides a finger piece 88 at its opposite end, for pivotal actuation of the member. The intermediate portion of the member is laterally enlarged at 90, and has formed therethrough an arcuate or curved slot 91 terminating in the central body zone of the member, in a slot opening 92 extending toward the finger 35 end of the member and defining a seat 94 and a camming lip 95. Shaft 82 extends through the slots of members 86, and since the shaft is confined by the carriage slots 84 to movement toward or away from the shaft of roll 76, pivotal movement of the members 86 will serve to position the roll 78 in operative adjacency to roll 76 or permit it to move away from the latter roll. For example, when the members 86 are pivoted each to a position such as shown in Fig. 8, the 40 roll 78 and its shaft 82 will be free for displacement away from the roll 76, since the curved slots 91 are in substantial registry with the slots 84. However, as the members 86 are pivoted to the dotted line position (Fig. 8), the curved slots 91 45 cam the shaft 82 toward roll 76, the shaft finally riding over the lips 95 and into seats 94, when the roll 78 will be substantially locked in predetermined relatively close operative relation to the roll 76. Release of roll 78 is effected by reverse 50 pivoting of the members 86 which effects initially, snap-movement of the shaft 82 over the lips 95, and thence camming of the shaft by the curved slots 91, to the free position of the roll 78.

The foregoing described release provision for 55 the roll 78 is here effected to facilitate insertion and mounting of the tube to be collapsed. When a tube is to be inserted in the device, the carriage is displaced to a point adjacent the clamp 25, and the roll 78 is released in the manner described. The sealed end of the tube is then passed

between the rolls 76 and 78, as permitted by free movement of roll 78 away from roll 76, and thence engaged by the jaws of the clamp 25 (Fig. 7). Thereafter, the roll 78 is returned to operative relation with roll 76, so that the rolls closely embrace the tube just forwardly of the sealed end 62 of the latter. In order to effect the initial relationship of the tube and press rolls, prior to tube-collapsing operation to dispense the tube contents, it may be necessary in some instances, to dispense a small amount of the tube content as by manual collapse of the tube at its sealed end, to provide sufficient collapsed surface immediately adjacent the tube sealed end, to receive the rolls thereagainst.

Actuation of the carriage and rolls in tube collapsing displacement along the tube, is effected in a novel and positive manner through actuating mechanism now to be described. Rotatably journaled on each stud 75 of carriage 67 and retained in axially spaced position thereon by suitable collars 100, is a gear wheel 101 which is sufficiently large in diameter to engage its teeth 102 in the teeth 104 of a straight rack 105 extending longitudinally in the base 11 of frame 10. Each rack is inwardly adjacent a side wall 12 of the frame, and extends substantially from end-to-end of the frame, as such appears in Fig. 3. A U-shaped operating member 106 has each arm 108 thereof extending between a gear wheel 101 and the adjacent side 68 of the carriage, to pivotal support on the stud 75. Spanning the arms 108 and freely pivoted thereto as at 109, is a pawl element 110 affording a pawl 112 near each end, for cooperation with the adjacent one of the gear wheels 101. The element 110 is provided with a depending lug or weight 113 offset from the pivotal axis of the element such as to bias the element (in the vertical mounting of the device) in the direction to engage its pawls with the gear wheels.

The operating member 106 is here limited in its pivotal movement to a predetermined, relatively short range of movement as determined by opposite abutments 114 and 116 formed on each side member 68 of the carriage, and positioned for cooperation with the arms 108 of the operating member (Figs. 6 and 7). The operating member 106 is urged or biased to a position wherein its arms 108 engage the abutments 114, by spring elements 117 each preferably coaxial with one of the carriage studs 75, and having one end 118 engaging or hooked-over an arm 108, and its opposite end 120 bearing against the projecting end 80 of the spindle 79 carrying the press roll 76.

The operating member 106 is provided with a projecting stem 121 terminating in a finger piece 122 for manual actuation of the member. Finger piece 122 is exposed on the front side of the closed casing members 18 and 19 (Figs. 1, 2 and 4), with the stem operating through a casing slot 124 provided by cut-away portions along the adjoining margins of the casing members.

In operation, following mounting of a tube to be collapsed and initial location of the compressor at the sealed end of the tube, downward pivoting of the operating member 106 from the abutments 114 to the abutments 116 (Fig. 6) will effect rotation of the gear wheels 101 through the engaged pawls 112. The gear wheels thus traveling on the racks 105, displace the carriage 67 forwardly along the tube from its sealed end, and the rolls 76 and 78 displaced with the carriage and freely rolling on the tube, collapse

the tube to dispense its contents. Prior to this operation, the valve element 47 is moved to register its port 52 with the port 46, so that in the dispensing operation the tube content may be discharged to use. A single operation of the member 106 will advance the carriage and press rolls only a relatively short distance, and hence the extent of tube collapse and amount of content discharged will be correspondingly small. Accordingly, by proper selection of the gear ratio of the gear wheel and rack assembly, as well as of the relative spacing of the abutments 114 and 116 limiting the extent of pivotal movement of the operating member 106, the amount of the tube content discharged in each actuation of the compressor may be predetermined such as to provide the desired quantity. In the instance of toothpaste for example, the dispenser may be adapted as aforesaid, to dispense in each actuation, an amount sufficient for one toothbrush application, the toothbrush of course, being held under the discharge end of the device, to receive the paste thereon.

A single actuation of the member 106 thus advances the compressor one step, the member thereafter being released or allowed to return to its position against abutments 114, under the urge of the return springs 117. The mechanism then is ready for a further dispensing step, such being repeated when desired, until the compressor finally attains the discharge end of the tube. At such time, the rolls 76 and 78 approach closely the head end 63 of the tube, and substantially all of the tube content is then dispensed.

From the foregoing description of operation, it will appear now that the present dispensing mechanism affords a step-by-step advance of the compressor in the tube collapsing direction, which is of great advantage for the reason hereinbefore noted. Moreover, the step-by-step, tube-collapsing advance of the compressor is attained by a positive drive as constituted by the operating member 106, pawls 112, gear wheels 101 and racks 105, the drive being fully effective to prevent retrograde movements of the compressor when the mechanism is in use to dispense the contents of a tube. The latter is in consequence of the pawls 112 engaging the gear wheels 101, since in the return of the operating member 106 to its initial position against abutments 114 (Fig. 6), the pawls engage the gear wheels to lock the compressor against backward movement.

It is to be noted that the compressor advancing drive may be readily released (see Fig. 7), merely by manual lifting of the pawl member through the weight projection 113, to hold the pawls 112 disengaged from the gear wheels 101. Thereafter, the compressor may be displaced freely along the trackway.

Provision is here made to permit assembly and disassembly of the compressor as a unit, relative to the frame 10. As will be noted in Figs. 6 and 7, each longitudinal frame slot 66 is laterally enlarged at 130 near the upper end of the frame, while the frame portion 131 terminating in the enlargement 130 is pressed outwardly from the plane of the frame side 12. Consequently, upon removal of the tube clamp 25, the entire compressor unit may be displaced upwardly from the frame, the casing members 18 and 19 of course being open at such time. The slot enlargements 130 and pressed out frame portions 131 readily permit passage of the studs 75, rollers 72 and 75 headed studs 71, out of slots 66 and past the up-

per end of the frame. Once removed, the compressor may be readily disassembled, as for repair or replacement of parts. When assembled, the unit is applied at the upper end of the frame to seat the rollers 72 in the frame slots 66 and thence the studs 75 in the slots, whereupon the compressor is displaced downwardly to permit re-assembly of the tube clamp 25.

The presently improved dispenser device is capable of accommodating collapsible tubes of various sizes and lengths, and is characterized by a positive and easily effected collapse of the tube in a step-by-step manner, from its sealed end to the head end of the tube, and such as to dispense from the tube substantially all of its content. Moreover, the advantages of the present device in respect to sanitation, are obvious, it being noted again that the valved port member is readily removable at will, to permit cleaning thereof.

Having described and illustrated a presently preferred embodiment of my invention, it is to be understood that modifications in the parts and operative arrangement thereof, may be made without departing from the spirit and full intended scope of the invention as defined by the appended claims.

I claim:

1. In a device for holding a collapsible tube and dispensing the contents thereof, a frame adapted for vertical mounting and providing a vertical trackway, means adjustably mounted on the frame near the upper end of the trackway, provided for clamping attachment to the sealed end of a collapsible tube to support the tube in suspension vertically along the trackway, means providing a valved discharge port, removably carried by the frame at the lower end of said trackway, an element on the last said means adapted for receiving the discharge end of the tube to locate the same in alignment with said valved discharge port, a compressor including freely rotatable tube press elements located for embracing the tube, guidedly supported relative to said trackway, and means for effecting step-by-step movement of said compressor in tube-collapsing advance along the tube, said means including a rack on said frame and substantially co-extensive with said

trackway, a gear rotatably carried by said compressor and engaging said rack, lever means including a pawl engageable with said gear, pivotally supported on the compressor, and stop means positioned on the compressor for engagement by said lever means to limit pivotal displacement of the latter.

2. In a device for dispensing the contents of a collapsible tube, a frame, supports thereon for the sealed and discharge ends of the tube, a carriage supported on the frame for movement along the tube, a first press roll including a shaft, freely rotatably supported on said carriage, a second press roll including a shaft, said carriage providing slots receiving the ends of the shaft of said second roll, said press rolls being freely rotatable and arranged for embracing the tube, said carriage slots permitting limited displacement of said second roll and its shaft away from an operative position relative to the other roll, to facilitate passage of the sealed end of the tube between the rolls in mounting the tube on said supports, latch means pivoted on the shaft of said first roll and engaging the shaft of said second roll, operable in latching position to retain said second roll in said operative position thereof, and actuating means for said carriage operable to effect step-by-step movement thereof in tube-collapsing advance along the tube.

DOUGLAS D. DERRICK.
